DESULFURIZATION OF CRUDE AND
CRACKED PETROLEUM DISTILLATESCharles O. Hoover, Houston, Tex., assignor to Air
Reduction Company, Incorporated, New York,
N. Y., a corporation of New York

Application April 22, 1947, Serial No. 743,170

16 Claims. (CL. 196—28)

1

This invention relates to the treatment of crude and cracked petroleum distillates for the purpose of reducing the sulfur content thereof, thereby affording products which are sweet and otherwise satisfactory for commercial use.

A considerable volume of the available crude petroleum includes substantial proportions of mercaptans, bisulfides, sulfides and hydrogen sulfide. These are known as "sour crudes." The sulfur compounds, either in their original or modified forms, are carried over in the distillates from such crudes and thus are found in the commercial products. No satisfactory and economical procedure for the elimination of sulfur from such products has been available heretofore.

It is the object of the present invention to afford a simple, effective and economical method for treating crude and cracked distillates in a continuous manner to remove the sulfur content.

Another object is the provision of a method of effecting regeneration of the treating material to eliminate the sulfur, thus permitting reuse of the material without substantial loss.

Other objects and advantages of the invention will be apparent as it is better understood by reference to the following specification and the accompanying drawing, which illustrates diagrammatically an apparatus suitable for the practice of the invention.

The invention is applicable to crude and cracked petroleum distillates such as distillates from crude petroleum, kerosene, gasoline, gas oil and the like. It depends upon the treatment of such vapors with a treating agent, preferably copper, copper oxide or copper hydrate, in the presence of an aliphatic or aromatic carboxylic acid which is sufficiently stable to permit vaporization and which forms, with the copper compound, a copper soap or copper compound of the acid. Such a copper compound of the organic acid is adapted to combine with sulfur present in the vapors, releasing thereby the organic acid which immediately recombines with the copper compound to again react with sulfur in the vapors. The copper and such compounds thereof as will react with the organic acid to form a copper compound with which the sulfurous material contained in the distillates will react to form stable copper-sulfur compounds are hereafter referred to as "cupreous material." As the result of these progressive reactions, the treating material acts progressively, that is to say, the lowermost layer in a column of the

2

material first becomes effective to remove sulfur, whereupon an overlying layer acts similarly, until the uppermost layer has been converted to a copper compound and has acted upon the vapors to remove the sulfur therefrom forming therewith stable copper-sulfur compounds. At this point, the material is no longer effective. It can, however, be regenerated readily by first flushing with an inert gas to remove the hydrocarbon vapors and thereafter oxidizing the copper-sulfur compounds with oxygen or air suitably diluted with an inert gas in order to control the temperature of combustion. The combustion eliminates the sulfur, which escapes as sulfur dioxide, and the material is then in suitable condition for reuse in the operation.

The treating material may consist of copper in the metallic form such as turnings or small pieces. If copper in the form of a powder is used, or if copper oxide, either cuprous or cupric, or copper hydrate is employed, these materials are preferably formed into pellets with suitable additions such as alumina or clay or other ceramic materials which afford an adequate body and prevent disintegration and the production of fines. In case metallic copper is employed, it is preferably subjected initially to oxygen or air at an elevated temperature to partially oxidize the copper.

It is essential, in starting the operation, that an aliphatic or aromatic carboxylic acid be present to combine with the copper to form a copper compound of the acid. In many cases, the petroleum vapors include naphthenic acid, and if a sufficient proportion is present, no addition is necessary. Otherwise the acid should be introduced in the form of vapor in sufficient quantity to combine with the cupreous material in the lowermost layer of the treating material. Acetic acid may be employed instead of naphthenic acid. In fact, any of the aliphatic or aromatic carboxylic acids which are stable at vaporizing temperatures are suitable for use in the method, since it is necessary merely to have present a sufficient amount of such an acid to form the copper compound which will react to combine with sulfur present in the vapors, forming water and releasing the acid for reaction with the overlying layer of the cupreous material.

The operation is conducted at an elevated temperature, sufficient only to maintain the particular material treated in the vapor form. Thus, the temperature at the top of the column of the treating material may range approximately from

400° to 800° F. Usually the temperature range is between 500° and 750° F. Lower or higher temperatures may be employed, depending upon the particular material which is treated.

In carrying out the invention, it is desirable to use two or more towers, in one or more of which the reaction is conducted while the spent material is re-oxidized in the other towers. Thus, the operation may be continuous, it being necessary merely to adjust the valves so that the 10 vapors are directed through an operating column while the oxidizing gas is passed through the spent material.

Referring to the drawing, 5 and 6 represent towers of any suitable construction having grids 7 and 8 to support the treating material 9 and 10 which is preferably in the form of pellets or pieces of the same or varying size. Grids 11 and 12 hold the treating material in the proper position.

A vaporizer or still 13 is adapted to hold the material to be treated and is heated in any suitable manner to provide vapor in a dome 14 which is delivered through a pipe 15 controlled by a valve 16 or through a branch 17 controlled by a valve 18 to one or the other of the towers 5 and 6. The towers are provided with drain outlets 19 and 20 controlled by valves 21 and 22 and with outlets 23 and 24 controlled by valves 25 and 26. Through the latter outlets sulfur dioxide is permitted to escape during the oxidizing operation.

In the event that the material treated does not include a sufficient acid content, an acid vaporizer 27, which is adapted to be heated by a coil 28, affords a supply of acid vapor which is delivered through a pipe 29 controlled by a valve 30, a branch 31 controlled by a valve 32 and a branch 33 controlled by a valve 34, to the respective columns 5 and 6. Thus acid in the proper proportion, that is sufficient to react with the cupreous material in the lower layer of treating material, may be introduced simultaneously with or previous to the introduction of the vapor from the vaporizer 13.

A pipe 35, connected to a source of inert gas, is provided with a branch 36 controlled by a valve 37 which is connected to the tower 5. A similar branch 38, controlled by a valve 39, is connected to the tower 6. Similarly, a pipe 40 is connected to a source of oxidizing gas such as oxygen or air which is supplied through connections 41 and 42 controlled by valves 43 and 44 to the respective columns.

An outlet pipe 45, controlled by a valve 46, is connected to the top of the tower 5 and to a pipe 47 controlled by a valve 48. Similarly a pipe 49, controlled by a valve 50, connects the top of the tower 6 to the pipe 47. A valve 51 is adapted to control delivery of vapor from one or the other of the towers 5 and 6 to a condenser 52 which is cooled by water circulating through the pipe 53. A pipe 54 delivers the condensed material to any suitable storage receptacle.

A pipe 55 controlled by valves 56 and 58 connects the tops of the towers 5 and 6 with a pipe 57 including a valve 59. The pipe 57 joins the pipe 28 and permits the return of acid vapors escaping from either of the towers 5 or 6 toward the end of the sulfur-removing cycle to the other tower, thus avoiding loss of any substantial portion of the acid.

If we assume that the tower 5 is ready for the sulfur-removing cycle, it is filled with the cupreous treating material 9, consisting essen-

tially of copper oxide. If the material to be treated contains insufficient acid, a suitable amount of acid is vaporized in the vaporizer 27 and delivered to the bottom of the column 5 through the connecting pipes to afford a layer of copper compound at the bottom of the column. Vapor from the vaporizer 13 is introduced, and the sulfur present in the vapor immediately combines with the copper compound, thereby releasing the acid which, being in vapor form, rises to the overlying layer of the treating material, combining therewith to form a copper compound which, in turn, removes the sulfur from the continuing stream of vapor. The reactions continue over a period of hours during which the layer of copper compound rises gradually in the tower 5 until the acid has reacted with material in the uppermost layer. At this point, the vapors, including the vaporized acid, are diverted through the pipe 51 by suitable manipulation of the valves and are delivered to the bottom of the tower 6.

Meanwhile, assuming that the tower 6 has previously been used, so that all of the material carried the sulfur which has been removed from vapors, the tower is first flushed by the introduction of inert gas from the pipe 35. When the hydrocarbon vapors have been removed, oxygen or air, suitably diluted with inert gas, is introduced from the pipe 40. At the temperature prevailing, the oxygen will immediately combine with the sulfur present. The oxidation is, of course, exothermic and must be controlled by the introduction of sufficient inert gas from the pipe 35 so that the temperature does not become excessive. The sulfur dioxide formed escapes through the pipe 24, the valves in the pipes 43 and 58 being closed at this period. When oxidation is complete, the tower is ready to receive the acid vapors which have been flushed from the tower 5 as previously described. If such acid vapors are not sufficient to cause the initial reaction and the formation of the copper compound, fresh acid vapors may be introduced from the acid vaporizer 27. Vapor from the vaporizer 13 is then diverted to the column 6, and the reactions proceed therein as previously described, while the treating material in the tower 5 is re-oxidized in the manner described in connection with the column 6. Any number of towers may be employed, the cycle of treatment and re-oxidation of the treating material being maintained so that while desulfurization is effected in one or more of the towers, regeneration of the material is carried out in the others.

The consumption of copper in the operation as described is practically nil, since it remains in the towers and there is no substantially possibility of loss. The reaction during the desulfurization of the material being treated involves only a thin deposit on the surface of the cupreous material, and the undesirable constituent of this film, i. e. sulfur, is converted to a volatile material, sulfur dioxide, which escapes as a gas. The only materials used are air and the small amount of acid which may be used in the event that the material treated does not include enough naphthenic acid to form sufficient copper naphthenate with the cupreous material. Most of the acid can be recovered and utilized in the manner described, and small losses thereof are readily made up at relatively slight expense.

The treating material may be packed in simple chambers such as the towers illustrated or in a group of smaller tubes surrounded by a heating

or cooling chamber, or the bed may be arranged to move through the reaction zone and then through a regenerating zone, after which it is returned for reuse. In other words, various types of apparatus may be adapted for the application of the method involving progressive formation of copper compound in a treating material and the subsequent regeneration of the material after it has removed sulfur from the material treated.

As an example of the invention, Hockley crude oil containing 2.11% of sulfur was treated in the manner described with the following results:

	Per cent Sulfur in Distillates from—		Per cent Sulfur Removed
	Untreated Crude	Treated Crude	
Gasoline Cut.....	0.213	0.060	76.5
Kerosene Cut.....	0.637	0.118	81.47
Gas Oil.....	1.327	0.420	68.3

Other similar operations have demonstrated the efficacy of the procedure in substantial reduction of the sulfur content of hydrocarbon vapors, thereby affording products which are sufficiently free from sulfur to be considered sweet.

Various changes may be made in the details of operation of the method as described, without departing from the invention or sacrificing the advantages thereof.

The term "sulfurous material" is used in the appended claims to denote sulfur in its elemental form, and sulfur compounds such as mercaptans, bisulfides, sulfides and hydrogen sulfide.

I claim:

1. The method of reducing the sulfur content of crude and cracked petroleum distillates which comprises introducing the vapor of an organic carboxylic acid at the bottom of a column consisting essentially of pieces of copper to form a layer of copper soap, directing the distillate in the vapor phase through the layer of copper soap thereby fixing the sulfur present on the copper and releasing the organic acid, and immediately combining the organic acid with the copper of the overlying layer for further desulfurization of the distillate.

2. The method of reducing the sulfur content of crude and cracked petroleum distillates which comprises introducing the vapor of an organic carboxylic acid at the bottom of a column consisting essentially of pieces of copper to form a layer of copper soap, directing the distillate in the vapor phase through the layer of copper soap thereby fixing the sulfur present on the copper and releasing the organic acid, immediately combining the organic acid with the copper of the overlying layer for further desulfurization of the distillate, and continuing the operation until substantially all of the copper of the column carries sulfur.

3. The method of reducing the sulfur content of crude and cracked petroleum distillates which comprises introducing the vapor of an organic carboxylic acid at the bottom of a column consisting essentially of pieces of copper to form a layer of copper soap, directing the distillate in the vapor phase through the layer of copper soap thereby fixing the sulfur present on the copper and releasing the organic acid, immediately combining the organic acid with the copper of the overlying layer for further desulfurization of the distillate, continuing the operation until substantially all of the copper of the column carries sul-

fur, and revivifying the spent column by oxidizing the sulfur.

4. The method of reducing the sulfur content of crude and cracked petroleum distillates as set forth in claim 1 in which the organic acid is naphthenic acid and the copper soap formed is copper naphthenate.

5. The method of reducing the sulfur content of petroleum distillates containing objectionable sulfurous material, which comprises bringing petroleum distillates containing objectionable sulfurous material and an organic carboxylic acid, in the vapor phase, into intimate contact with pieces of cupreous material, whereby the organic acid reacts with said cupreous material to form a copper compound of the acid, and the sulfurous material in the petroleum distillates reacts with the thus-formed copper compound to form stable copper-sulfur compounds and to liberate the organic acid, and bringing the thus-liberated organic acid into intimate contact with more cupreous material to form more copper compound for reaction with more of the vaporized distillates.

6. The method of reducing the sulfur content of petroleum distillates containing objectionable sulfurous material as set forth in claim 5 in which the organic acid is naphthenic acid and the copper compound formed is copper naphthenate.

7. The method of reducing the sulfur content of petroleum distillates containing objectionable sulfurous material which comprises passing petroleum distillates containing objectionable sulfurous material, in the vapor phase, into intimate contact with a copper compound of an organic carboxylic acid, whereby the sulfurous material in the distillates reacts with the copper compound to form stable copper-sulfur compounds and to liberate the organic carboxylic acid corresponding to said copper compound, and bringing the thus liberated organic acid into intimate contact with pieces of a cupreous material to form more copper compound for reaction with more of the vaporized distillates.

8. The method of reducing the sulfur content of petroleum distillates containing objectionable sulfurous material as set forth in claim 7 in which the cupreous material is copper.

9. The method of reducing the sulfur content of petroleum distillates containing objectionable sulfurous material as set forth in claim 7 in which the cupreous material is copper oxide.

10. The method of reducing the sulfur content of petroleum distillates containing objectionable sulfurous material as set forth in claim 7 in which the copper compound is copper naphthenate and the organic acid is naphthenic acid.

11. The method of reducing the sulfur content of petroleum distillates containing objectionable sulfurous material as set forth in claim 10 in which the cupreous material is copper.

12. The method of reducing the sulfur content of petroleum distillates containing objectionable sulfurous material as set forth in claim 10 in which the cupreous material is copper oxide.

13. The method of reducing the sulfur content of petroleum distillates which comprises passing the petroleum distillates containing objectionable sulfurous materials, in the vapor phase, into intimate contact with a copper compound of an organic carboxylic acid, whereby the sulfurous material in the distillates reacts with the copper compound to form stable copper-sulfur compounds and to liberate the organic carboxylic acid corresponding to the copper compound, bringing the thus-liberated organic acid into intimate con-

tact with pieces of a cupreous material to form more copper compound for reaction with more of the vaporized distillates, continuing to pass sulfurous-containing petroleum distillates, in the vapor phase, through the cupreous material with continued successive reaction of the sulfurous material with copper compound formed and liberation of organic acid for forming more copper compound until substantially all of the cupreous material has been converted into stable copper-sulfur compounds, then discontinuing the passing of the distillates through the cupreous material, and bringing an oxidizing agent into intimate contact with the copper-sulfur compounds under oxidizing conditions, whereby the sulfur of the copper-sulfur compounds is oxidized to sulfur dioxide which escapes as a gas and the cupreous material is regenerated.

14. The method of reducing the sulfur content of petroleum distillates containing objectionable sulfurous material as set forth in claim 13 in which the copper compound is copper naphthenate and the organic acid is naphthenic acid.

15. The method of reducing the sulfur content of petroleum distillates containing objectionable sulfurous material which comprises forming a body of pieces of a copper compound of an organic carboxylic acid, forming a body of pieces of a cupreous material which will react with an organic carboxylic acid to form a copper compound corresponding to the organic carboxylic acid, and passing the petroleum distillates containing the objectionable sulfurous material, in the vapor phase, into intimate contact successively with the body of copper compound and then with the body of cupreous material, the sulfurous material in the distillates reacting with the copper compound to form stable copper-sulfur compounds and to liberate the organic carboxylic acid corresponding to the copper compound, and the thus-liberated organic carboxylic acid reacting with the body of cupreous material to form the corresponding copper compound for reaction with more of the sulfurous material in the vaporized distillates.

16. The method of reducing the sulfur content of petroleum distillates containing objectionable sulfurous material which comprises forming a body of pieces of a copper compound of an organic

10
